UNITED STATES PATENT OFFICE.

CARL EDUARD PETERSEN, OF COPENHAGEN, DENMARK.

ADVERTISING APPARATUS.

No. 899,467.

Specification of Letters Patent. Patented Sept. 22, 1908.

Application filed March 21, 1907. Serial No. 363,765.

To all whom it may concern:

Be it known that I, CARL EDUARD PETERSEN, a subject of the King of Denmark, residing at Copenhagen, Denmark, have invented 5 certain new and useful Improvements in Advertising Apparatus, of which the following is a full, clear, and exact description.

This invention relates to an advertising apparatus principally intended to be used in 10 shop windows and similar places.

A form of the invention is shown in the drawing in which:

Figure 1 is a top view of the apparatus; Fig. 2 is a side view with one side of the box 5 removed, and Figs. 3, 4, and 5 illustrate details. Fig. 6 is a detail view showing a modification.

Referring to the drawing, *a* designates a box having a vertical revoluble spindle *c* 10 driven from a motor *b* by a belt or any other connection.

d is a magnetic bobbin or coil surrounding the spindle *c* and receiving current through rings *e* engaged by the brushes *l*. The upper 5 end of the spindle *c* projects through the top *g* of the box which is preferably made of glass.

h designate a plurality of loops or devices of iron wire or similar magnetic substance which are adapted to rest loosely on the 10 cover *g* of the box and to be frictionally en-

gaged by the magnetized end of the spindle *c*. In this relation these loops or devices are caused to describe various erratic movements when the spindle rotates. Figs. 3, 4 and 5 illustrate forms of loops or devices *h* which 35 may be used and which describe different movements. These devices may be used to support a tray or other object which is thereby given a corresponding movement so as to attract attention. In Fig. 6 the loops or devices *h* are made of round wire and the upper end of the spindle *c* has a grooved pulley so as to make a good contacting engagement with the wire.

What I claim is:

An advertising device comprising a box having a vertical revoluble spindle, a motor belted thereto, a magnetic bobbin surrounding such spindle and having a pair of collector rings, brushes engaging said rings, a glass 50 cover for said box through which said spindle projects, and iron loops or devices of irregular shapes loosely received on said cover and engaged by said spindle.

In witness whereof, I subscribe my signature, in the presence of two witnesses.

CARL EDUARD PETERSEN.
